UNITED STATES PATENT OFFICE.

HAROLD M. SANFORD, OF SAN ANTONIO, TEXAS.

INTERNAL-COMBUSTION MOTOR.

1,372,250.

Specification of Letters Patent. Patented Mar. 22, 1921.

Application filed January 12, 1920. Serial No. 350,889.

To all whom it may concern:

Be it known that I, HAROLD M. SANFORD, citizen of the United States, residing at San Antonio, in the county of Bexar and State of Texas, have invented certain new and useful Improvements in Internal-Combustion Motors, of which the following is a specification.

This invention relates to new and useful improvements in an internal-combustion motor.

One object of the invention is to provide an internal combustion motor having a cylinder formed of a stationary sleeve and provided with an intake and an exhaust port and a rotatable sleeve fitted around the stationary sleeve and provided with corresponding ports adapted to be brought into and out of registration with the intake and exhaust ports, thus forming an intake and an exhaust valve which controls said ports and further embodies means for actuating said rotatable sleeve.

Another object of the invention resides in the provision of an improved method of lubricating the rotatable sleeve and the mechanism through which said sleeve is actuated.

A still further feature of the invention resides in the provision of a motor of the character described, whose parts are readily accessible, thus facilitating repairs, and which may be readily removed for replacement.

With the above and other objects in view, the invention has particular relation to certain novel features of construction, operation and arrangement of parts, an example of which is given in this specification and illustrated in the accompanying drawings wherein:—

Figure 1, is a vertical sectional view of one of the cylinders of the motor,

Fig. 2, is a plan view of the motor,

Fig. 3 is a side elevation thereof shown partially in section and

Fig. 4 shows a fragmentary plan view of the rotating sleeve and the actuating mechanism thereof.

Referring now more particularly to the drawings wherein like numerals of reference designate similar parts in each of the figures, the numeral 1 refers to the motor, which is shown of the four cylinder type, the numeral 2 designates the intake manifold through which the motive fluid is delivered

to the respective cylinders and the numeral 3 designates the exhaust manifold through which the spent gases are delivered from said cylinders. Each cylinder is formed of a stationary sleeve 4 formed of double walls, thus providing a chamber 5 for the circulation of water therethrough to cool the cylinder and the heads 6 and 7 are provided which are threaded into the open ends 60 of these walls to close the same, said heads being integrally connected by means of the tubular neck 8 which is internally threaded to receive the spark plug 9. Chamber 5 has the inlet water pipe 10 and the outlet water pipe 11 provided for the circulation 70 of water through said chamber. The stationary sleeve has an intake port 12 and an exhaust port 13, arranged substantially opposite the intake port, and these respective intake and exhaust ports of the cylinders are connected to the intake and exhaust manifolds 2 and 3.

Surrounding each stationary sleeve there is a rotatable sleeve 14 which is provided 80 with intake and exhaust ports 15 and 16 so disposed as to be brought into and out of registration with the respective ports 12 and 13 as the sleeve 14 rotates. Fastened to the upper end of each sleeve 14 there is an 85 annular screw gear 17 and in mesh with said screw gears there are the corresponding screw gears 18, which are fastened upon the lengthwise shaft 19. This shaft and the gears thereof are inclosed in the long casing 20 designed to contain a lubricant for 90 lubricating said gears and each rotatable sleeve 14 is provided with the lubricating ports 21 which communicate with the chamber within the casing 20 and the lubricant 95 within said chamber finds its way through said ports between said sleeves, and directly from said chamber around the rotatable sleeve, and provision is thus made for constantly lubricating the sleeves. The rotatable sleeve is mounted to rotate on an 100 antifriction bearings 22, as illustrated in Fig. 1 to reduce the friction thereof.

The shaft 19 is rotatably mounted in suitable bearings 23 carried by the top of 105 the motor and one end thereof has the sprocket wheel 24 fixed thereon in alignment with the sprocket wheel 25 which is fixed upon the drive shaft 26 and operating over these sprocket wheels and transmitting rotation from the latter to the former is the sprocket chain 27. Through

the mechanism described the shaft 19 is rotated and rotation is thus imparted to the rotatable sleeve 14 through the gearing described. The mechanism is so timed as to 5 register the intake and exhaust ports of the rotatable and stationary sleeves at the proper time to admit the charge and discharge the spent gases.

Within the respective cylinders are the 10 pistons 28 which are connected to the crank shaft 29 through the connecting rods 30.

The respective cylinder heads are secured to the cylinders by means of bolts as 15 and said bolts may be removed permitting the removal of the stationary sleeve 4 for cleaning and repairing the same and when said stationary sleeve is removed, the rotatable sleeve may then also be readily withdrawn.

20 What I claim is:

1. In an internal combustion motor, a cylinder formed of a stationary sleeve provided with an intake and an exhaust port a surrounding rotatable sleeve provided with 25 corresponding ports adapted to register with the ports of the stationary sleeve, a

mechanism operatively connected with and driven from the motor crank shaft and also operatively connected with said rotatable sleeve and driving the same, an inclosing 30 casing for said driving means, forming a chamber, provided to contain a lubricant, the rotatable sleeve having ports which communicate with said chamber and through which a lubricant is admitted between said 35 sleeves.

2. In an internal combustion motor a stationary, and a surrounding rotatable sleeve, the latter having lubricant ports, a casing forming an inclosed lubricant chamber; a 40 mechanism within the chamber for driving the rotatable sleeve, said chamber being located to deliver a lubricant around the rotatable sleeve, and through said ports between said sleeves.

45 In testimony whereof I have signed my name to this specification in the presence of two subscribing witnesses.

HAROLD M. SANFORD.
